METAL-ACI-SALTS OF NITRO COMPOUNDS
 Milton B. Frankel, Pasadena, Calif., assignor to Aerojet-General Corporation, Azusa, Calif., a corporation of Ohio
 No Drawing. Filed Aug. 7, 1957, Ser. No. 677,193
 20 Claims. (Cl. 260—644)

This invention relates to new compositions of matter and methods of synthesizing them. In particular, it relates to metal-aci-salts of nitroalkyls having the general formula:

wherein M is a metal radical of an alkali or alkaline earth metal element, and R is a nitroalkyl radical.

The polynitro compounds of this invention, because of their favorable oxygen balance, find valuable use as burning rate accelerators for rocket propellants. In addition, they are useful as high explosives and can be used in any conventional explosive missile, projectile, rocket, or the like, as the main explosive charge. An example of such a missile is disclosed in U.S. Patent No. 2,470,162, issued May 17, 1949. One way of using the high explosives in a device such as that disclosed in U.S. Patent No. 2,470,162 is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time-fuse mechanism firing a detonating explosive such as lead azide or mercury fulminate.

The nitro compounds of this invention are conveniently prepared in accordance with the general reaction scheme set forth below:

wherein X is a halogen radical, M and R are as defined above, and R' is an alkyl radical.

The following examples are presented to more clearly illustrate my invention. It should be understood that these examples are intended to merely illustrate the invention, and should not be interpreted to limit the scope of this invention in any manner.

EXAMPLE I

Formation of sodium-aci-1,1,3-trinitrobutane from sodium-aci-nitroethane

A 3-necked reactor was fitted with a mechanical stirrer, thermometer and dropping funnel and charged with a suspension of 490 gm. (5 mole) of sodium nitroethane and 1500 ml. of methanol. A solution of 640 gm. (2.5 mole) of 2-bromo-2,2-dinitroethyl acetate in 1500 ml. of methanol was added while maintaining the temperature between 10–15° C. The white suspension of the salt became orange as the reaction proceeded and gradually went into solution. The solution was evaporated to dryness leaving an orange salt; this salt being sodium-aci-1,1,3-trinitrobutane.

EXAMPLE II

Formation of sodium-aci-1,1,3,3-tetranitrobutane from sodium-aci-1,1-dinitroethane

A 3-necked flask, fitted with a mechanical stirrer, ther-

2

mometer, and dropping funnel was charged with 1 mole of 1,1-dinitroethane. The reactor was cooled in an ice bath and a solution containing 1 mole of sodium hydroxide in water was added. To this solution, a solution of 5 2-bromo-2,2-dinitroethyl acetate in methanol was added dropwise with stirring until half a mole of the 2-bromo-2,2-dinitroethyl acetate had been added. The solution to which the methanol solution was added was maintained at 10° C. until the dropwise addition of the latter was 10 completed. The final solution was allowed to warm to room temperature with stirring, after which it was extracted with ether to remove any unreacted starting materials. The aqueous layer resulting from the ether extraction was to 5° C. This layer contained sodium-aci- 15 1,1,3,3-tetranitrobutane as the final product.

Various other metal salts such as those of magnesium, barium, lithium, potassium, etc., can be prepared in accordance with the examples set forth above. In many instances, however, because of solubility problems, it 20 may be desirable to use an alternative method. Sodium salts as prepared above are readily converted to their corresponding halogen derivatives through the reaction of bromine or chlorine water. The halogen substituted composition thus obtained readily undergoes conversion 25 to the desired metal salt by the action of an alkali or alkaline earth metal iodide in alcoholic solution. The following examples are provided to more clearly illustrate this alternative synthesis.

EXAMPLE III

Preparation of 1-bromo-1,1,3,3-tetranitrobutane

An aqueous solution of sodium-aci-1,1,3,3-tetranitrobutane was cooled to about 5° C. and treated with 0.5 mole of bromine. The solution was extracted with ether 35 and then dried and concentrated. 1-bromo-1,1,3,3-tetranitrobutane was obtained in good yield.

EXAMPLE IV

Preparation of potassium-aci-1,1,3,3-tetranitrobutane

40 1-bromo-1,1,3,3-tetranitrobutane was dissolved in methanol and cooled to 0° C. The solution was treated with potassium iodide in 50% methanol. A purple reaction mixture formed which was filtered off leaving a 45 yellow salt, which was washed with ether and recrystallized from ethanol. The product was subsequently identified as potassium-aci-1,1,3,3-tetranitrobutane, having a melting point of 137–138° C. Analysis was as follows:

Calculated: percent C, 17.39; percent H, 1.83; percent N, 50 20.29. Found: percent C, 17.71; percent H, 1.83; percent N, 20.69.

While the examples have been limited to the use of bromine compositions as starting materials, the other 55 halogens can also be employed in this reaction. Similarly, any of the alkali and alkaline earth metal nitroalkyl compounds can be reacted to effect a direct synthesis of the metal salts of this invention.

Thus, esters such as 2-chloro-2,2-dinitroethyl propionate; 2-iodo-2,2-dinitroethyl valerate; and 2-fluoro-2,2-dinitroethyl butyrate react with lithium-aci-1,1-dinitropropane; magnesium-aci-1,1,3,3-tetranitrobutane; and calcium-aci-1,1,3,3-tetranitropentane to yield lithium-aci-1,1,3,3-tetranitropentane; magnesium-aci-1,1,3,3,5,5-hexanitrohexane; and calcium-aci-1,1,3,3,5,5-hexanitroheptane, respectively. It is apparent that any member of my series of new compounds can be produced by reacting appropriate starting materials as taught herein.

Reaction temperature is not critical in the practice of 70 the present invention, the only effect of temperature variation being a corresponding increase or decrease in the rate of reaction.

This application is a continuation-in-part of my co-pending U.S. patent application Ser. No. 451,704, filed August 23, 1954, now abandoned, which was a continuation-in-part of my U.S. patent application Ser. No. 248,876, filed September 28, 1951, now abandoned.

I claim:

1. As compositions of matter, the alkali and alkaline earth metal-aci-salts of nitro compounds, having the formula:

wherein R is a lower nitroalkyl radical and M is a metal radical selected from the group consisting of alkali and alkaline earth metals.

2. As compositions of matter, the alkali and alkaline earth metal-aci-salts of nitro compounds, having the formula:

wherein A is a radical selected from the group consisting of hydrogen and lower alkyl radicals and M is a metal radical selected from the group consisting of alkali and alkaline earth metals.

3. As compositions of matter, the alkali and alkaline earth metal-aci-salts of nitro compounds, having the formula:

wherein A is a radical selected from the group consisting of hydrogen and lower alkyl radicals and M is a metal radical selected from the group consisting of alkali and alkaline earth metals.

4. As a composition of matter, sodium-aci-1,1,3-trinitrobutane having the structural formula:

5. As a composition of matter, sodium-aci-1,1,3,3-tetranitrobutane having the structural formula:

6. As a composition of matter, potassium-aci-1,1,3,3-tetranitrobutane having the structural formula:

7. As a composition of matter, lithium-aci-1,1,3-tetranitropentane.

8. As a composition of matter, magnesium-aci-1,1,3,3,5,5-hexanitrohexane.

9. As a composition of matter, calcium-aci-1,1,3,3,5,5-hexanitroheptane.

10. The method of preparing alkali and alkaline earth metal-aci-salts of nitro compounds having the formula:

which comprises reacting an ester having the formula:

with a metal-aci-salt having the formula:

wherein X is a halogen radical, M is a metal radical selected from the group consisting of the alkali and alkaline earth metals, R is a lower nitroalkyl radical, and R' is a lower alkyl radical.

11. The method of preparing sodium-aci-salts of nitro compounds, having the formula:

which comprises reacting an ester having the formula:

with a sodium-aci-salt having the formula:

wherein R is a lower nitroalkyl radical and R' is a lower alkyl radical.

12. The method of preparing sodium-aci-1,1,3-trinitrobutane which comprises reacting 2-bromo-2,2-dinitroethyl acetate with sodium-aci-nitroethane.

13. The method of claim 12 wherein the reaction is conducted in the presence of an inert organic solvent.

14. The method of preparing sodium-aci-1,1,3,3-tetranitrobutane which comprises reacting 2-bromo-2,2-dinitroethyl acetate with sodium-aci-1,1-dinitroethane.

15. The method of claim 14 wherein the reaction is conducted in the presence of an inert organic solvent.

16. The method of preparing lithium-aci-1,1,3,3-tetranitropentane which comprises reacting 2-chloro-2,2-dinitroethyl propionate with lithium-aci-1,1-dinitropropane.

17. The method of preparing magnesium-aci-1,1,3,3,5,5-hexanitrohexane which comprises reacting 2-iodo-2,2-dinitroethyl valerate with magnesium-aci-1,1,3,3-tetranitrobutane.

18. The method of preparing calcium-aci-1,1,3,3,5,5-hexanitroheptane which comprises reacting 2-fluoro-2,2-dinitroethylbutyrate with calcium-aci-1,1,3,3-tetranitropentane.

19. The method of preparing potassium-aci-1,1,3,3-tetranitrobutane which comprises reacting an ester having the formula:

with sodium-aci-1,1-dinitroethane to obtain sodium-aci-1,1,3,3-tetranitrobutane; reacting the sodium-aci-1,1,3,3-tetranitrobutane with bromine to obtain 1-bromo-1,1,3,3-tetranitrobutane; and reacting the 1-bromo-1,1,3,3-tetranitrobutane with potassium iodide; wherein X is a halogen radical and R' is a lower alkyl radical.

20. The method of claim 19 wherein the reaction between the 1-bromo-1,1,3,3-tetranitrobutane and the potassium iodide is conducted in alcoholic solution.
